REMOTE CONTROL APPARATUS

Ronald A. McCann, Swissvale, Pa., assignor to
The Union Switch & Signal Company, Swiss-
vale, Pa., a corporation of Pennsylvania

Application November 18, 1931
Serial No. 575,759

3 Claims. (Cl. 246—3)

My invention relates to remote control apparatus, and particularly to apparatus for controlling railway traffic governing devices, such as track switches, from a distant point.

5 One feature of my invention is the provision of apparatus which requires contemporaneous action by two persons for releasing a railway track switch for manual operation.

10 I will describe one form of apparatus embodying my invention, and will then point out the novel features thereof in claims.

The accompanying drawing is a diagrammatic view showing one form of apparatus embodying my invention.

15 Referring to the drawing, the reference characters 1 and 1^a designate the rails of a stretch Y of railway track which includes switches W¹ and W² for connecting stretch Y with passing sidings Z¹ and Z², respectively. Rails 1 and 1^a of stretch Y are divided by means of insulated joints 2 into sections A—B, B—C, etc. Each of these track sections is provided with a track circuit including a battery 3 connected across the rails adjacent one end of the section, and a relay designated by the reference character R with a distinguishing exponent and connected across the rails adjacent the opposite end of the section.

20 Each of the switches W may be operated by any suitable manually operable mechanism, not shown in the drawing. A lock bar b is rigidly secured to each of the switches W¹ and W² for engagement with a dog a, by means of which the switch may be locked in its normal position in which it is shown in the drawing. Each dog a is actuated by means of a manually operable lever which is designated by the reference character V with a distinguishing exponent, and which has normal and reverse positions designated by the reference characters n and r, respectively. Movement of each lever V is controlled by a lock magnet d having an armature provided with a dog 26 for engagement with a notch 27 of a locking segment g. The armature 25 of each magnet d also operates a back contact 11. Each segment g is rigidly connected with its lever V. Each lever V operates a contact 19 which is closed when and only when the lever is in its normal position.

30 Each lever V and its magnet d are enclosed in a case having a door which operates a contact designated by the reference character f with a corresponding exponent. Each of the contacts f is closed when and only when the corresponding door is open.

Each switch W operates a contact 10 which is closed when and only when the switch occupies its normal position in which it is shown in the drawing.

35 A signal S governs westbound traffic movements over switches W¹ and W², that is, traffic movements from right to left as shown in the drawing.

A track circuit repeater relay, designated by the reference character T^{P2}, is controlled by front contacts of track relays R², R³, R⁴ and R⁵. A second track circuit repeater relay T^{P1} is controlled by front contacts of relays R¹ and T^{P2}.

40 Each of the lock magnets d is controlled by contact 19 of the corresponding lever V, by front contacts 20 and 21 of a relay which is designated by the reference character L with a corresponding exponent, and by either a front contact 22 of the associated relay T^P or by a back contact 23 of an associated track relay R.

45 Each of the relays L¹ and L² is of the type having a pick-up winding 24 and a holding winding 25. The pick-up circuits for relays L are controlled by manually operable devices which are here shown as push buttons designated by the reference character P with distinguishing exponents. The stick circuit for each of these relays is controlled by contact 19 of the associated lever V. Both the pick-up and stick circuits for relays L are controlled by a door contact f.

50 Each of the push buttons P² and P³ is provided with a normally open contact which may be closed manually, and which will remain closed only when manually held in that condition. Push button P¹ is provided with a normally closed contact and with a normally open contact. The normally closed contact will remain closed except when push button P¹ is manually operated to open this contact or to close its back contact. The back contact of push button P¹ will remain closed only when manually held in this condition. These characteristics of the several push buttons are illustrated by a biasing spring 40 applied to button P².

55 An indication relay K is controlled by each of the switch contacts 10, by each of the back contacts 11 of magnets d, and also by the back contact 12 of each of the relays L. Relay K can therefore be energized only when both switches W are in the normal position, and when both lock magnets d and both relays L are deenergized.

60 An indication device, which is here shown as an indicator lamp e, is controlled by relay K so as to indicate the condition of relay K.

65 Push button P³, relay K, and indicator lamp e

may be located at some remote point, such for example as a despatcher's office.

A signal relay H is controlled by a front contact of relay K, as well as by front contacts of relays R¹, R² and R³. Relay H, when energized, causes the arm of signal S to be operated to the caution position.

As shown in the drawing, all parts are in the normal condition, that is, each of the track sections is unoccupied, each of the switches W is in its normal position, and each of the push buttons P is in its normal position. With the track sections unoccupied, each of the relays R is energized, causing the relays T^{P1} and T^{P2} to be energized. The circuit for relay T^{P2} passes from terminal x of a source of current not shown in the drawing, through front contact 4 of relay R⁵, contact 5 of relay R⁴, contact 6 of relay R³, contact 7 of relay R², and the winding of relay T^{P2} to terminal o of the same source of current. The circuit for relay T^{P1} passes from terminal x, through contact 8 of relay T^{P2}, contact 9 of relay R¹, and the winding of relay T^{P1} to terminal o. On account of switches W being in the normal position, and on account of push buttons P being in their normal positions, relay K is energized by a circuit passing from terminal x, through contact 10 of switch W², contact 11 of magnet d for switch W², contact 12 of relay L², contact 10 of switch W¹, contact 11 of magnet d for switch W¹, contact 12 of relay L¹, and the winding of relay K to terminal o. With relay K energized, indicator lamp e is lighted by its circuit through contact 13 of relay K. Also on account of relay K being energized and on account of the track sections being unoccupied, signal relay H is energized by a circuit passing from terminal x, through contact 14 of relay K, contact 15 of relay R¹, contact 16 of relay R², contact 17 of relay R³, and the winding of relay H to terminal o. With relay H energized, the arm of signal S is held in its caution position by a circuit passing through contact 18 of relay H.

I will now assume that the despatcher desires to permit a train to pass over switch W² into siding Z². Accordingly, the despatcher will momentarily depress push button P³ while a trainman is depressing push button P² after having opened the door of the case associated with switch W² thereby closing contact f².

The pick-up winding for relay L² will therefore be energized by a circuit passing from terminal x, through the contact of push button P³, the front contact of push button P¹, the contact of push button P², winding 24 of relay L², and contact f² to terminal o. Upon the energization of relay L², a stick circuit is completed for this relay, passing from terminal x, through contact 19 of lever V², contact 20 of relay L², winding 25 of relay L³, and door contact f² to terminal o. Relay L², upon becoming energized, opens its back contact 12, thereby interrupting the circuit for relay K. Relay K becoming deenergized, the contact 13 of this relay will open, and extinguish indicator lamp e, thus indicating to the despatcher the energization of relay L². The deenergization of relay K also causes its contact 14 to open in the circuit for relay H, which is, however, already open on account of relay R² being deenergized because the train is in section B—C preparatory to moving over switch W² reversed.

Relay R² being deenergized, magnet d for switch W² will now be energized by a circuit passing from terminal x, through contact 19 of lever V², contacts 20 and 21 of relay L², contact

23 of relay R², and the winding of magnet d to terminal o. The energization of magnet d opens its contact 11 in the circuit for relay K, which is, however, already open at contact 12 of relay L². With magnet d energized, dog 26 will be out of engagement with notch 27 of the corresponding segment, and hence the trainman can move lever V² to withdraw dog a from bar b. The trainman can then proceed to reverse switch W².

The reversal of switch W² opens its contact 10 in the circuit for relay K, which is, however, already open at contact 12 of relay L² and at contact 11 of magnet d.

If, after the train has moved into siding Z² and has cleared track section C—D, permitting relay R³ to become energized, the trainman returns switch W² to its normal position and, further, assuming that the other track sections shown in the drawing are all unoccupied, the apparatus will be returned to its normal condition previously described, provided the door of the casing has been closed.

I will now assume that afterwards the train is ready to leave siding Z² and to continue its movement westward. The trainman will notify the despatcher by some suitable means, such for example as a telephone, that the train is ready, and the despatcher will again momentarily depress push button P³ while the trainman depresses push button P² and opens the door of the casing, for causing relay L² to again become energized. Relay L², upon becoming energized, causes magnet d to become energized by a circuit which is the same as the circuit previously traced, except for including a branch path through front contact 22 of relay T^{P2}, around contact 23 of relay R². The indicator lamp e will function as before to indicate to the despatcher when relay L² becomes energized. When magnet d has become energized, the trainman will again reverse switch W² to permit the train to enter stretch Y. After the train has entered stretch Y and the trainman has restored switch W² to its normal position, relays R² and R¹ will successively become energized as the train leaves sections B—C and A—B. After the train has left section A—B, the apparatus will be in its normal condition previously described, provided the door of the casing has been closed.

The operation of the apparatus for a train to move over switch W¹ reversed, either from stretch Y to siding Z¹, or from siding Z¹ to stretch Y, is similar to that just described in connection with switch W², except that the trainman instead of depressing push button P² will depress push button P¹.

I have described for a few typical traffic movements the operation of the apparatus embodying my invention. From these descriptions and from the accompanying drawing, the operation of the apparatus for every other possible traffic movement will be readily understood without further explanation.

Apparatus embodying my invention requires contemporaneous action by the despatcher and by a trainman to release a switch for manual operation. The despatcher can not therefore store the control of the switch without the cooperation of a trainman. When a relay L has become energized, it will remain energized only if the door of the corresponding one of the cases containing levers V¹ or V² is left open. As long as a relay L remains energized, signal S will indicate "stop" and indicator lamp e will be extinguished, hence the despatcher will know at all times whether the

apparatus is in condition for releasing the switch W^1 or W^2 , and signal S will give similar information to trainmen.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track switch, a lever for controlling said switch, an electric lock, means controlled by said lock for controlling said lever, a manually operable push button contact, a second manually operable push button contact located at a point remote from said first push button contact, a stick relay having a pick-up and a stick circuit one of which is controlled by said 15 push button contacts in series and the other of which is controlled by said lever, and means controlled by said relay for controlling said lock.

2. In combination, a railway track switch, a lever for controlling said switch, an electric lock magnet, means controlled by said lock magnet for controlling said lever, a manually operable push button contact, a second manually operable push button contact located at a point remote from said first push button contact, a stick relay 20 having a pick-up and a stick circuit one of which

is controlled by said push button contacts in series and the other of which is controlled by said lever, means for energizing said lock magnet only when said relay is energized, a signal governing traffic movements over said switch, and means for 80 energizing said signal only when said relay is deenergized.

3. In combination, a railway traffic governing device, a normally open contact which is manually operable to its closed position and which will remain closed only when manually held in that condition, a second normally open contact located at a point remote from said first contact and which is also manually operable to its closed position and which will remain closed only when manually held in that condition, a circuit controller having a normally open contact and a normally closed contact and which is arranged to retain said contacts in these conditions except when manually held in a position for opening the normally closed contact or for closing the normally open contact, a circuit including said first contact and the normally open contact of said circuit controller in series for controlling said traffic governing device, a second railway traffic 95 governing device, and a circuit including said first and second contacts and the normally closed contact of said circuit controller in series for controlling said second traffic governing device.
